CLAIM

The ornamental design for a toy basketball goal, as shown and described.

DESCRIPTION

FIG. 1 is a left side elevational view of a toy basketball goal showing my new design, the right side elevation being a mirror image;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left-side elevational view on a reduced scale in an extended position.
